UNITED STATES PATENT OFFICE

EDGAR F. STINER, OF NEW YORK, N. Y.

DESIGN FOR A LACE SCARF OR SIMILAR ARTICLE

Application filed September 26, 1930. Serial No. 37,076. Term of patent 3½ years.

To all whom it may concern:

Be it known that I, EDGAR F. STINER, a citizen of the United States, residing at New York, in the county of New York and State of New York, have invented a new, original, and ornamental Design for Lace Scarf or Similar Article, of which the following is a specification, reference being had to the accompanying drawing, forming part thereof.

The figure is a plan view of one-half of a lace scarf or similar article, one-fourth of the scarf being illustrated in detail at the right hand side of the drawing. The remaining three-fourths of the scarf are repetitions of the detailed illustrations in proper relation thereto to complete the article.

I claim:

The ornamental design for a lace scarf or similar article as shown and described.

EDGAR F. STINER.
